UNITED STATES PATENT OFFICE.

ANTON SCHROEDER, OF ST. PAUL, MINNESOTA.

HANGER FOR STORM-SASH.

1,366,599.

Specification of Letters Patent. Patented Jan. 25, 1921.

Application filed May 6, 1920. Serial No. 379,251.

To all whom it may concern:

Be it known that I, ANTON SCHROEDER, a citizen of the United States, residing at St. Paul, in the county of Ramsey and State 5 of Minnesota, have invented certain new and useful Improvements in Hangers for Storm-Sash, of which the following is a specification.

This invention relates to hangers for 10 storm sash and the like, and has for its object to provide a hanger so constructed as not to rattle on its support.

A further object of the invention is to provide a hanger which may be stamped and 15 formed out of sheet metal requiring no subsequent filing or machine work as far as the working parts are concerned.

It has been found very difficult to produce 20 an article of this kind from sheet metal which will not require to be made with a great deal of play in the parts so as to render it practical from a manufacturing standpoint. For this reason hangers rattle under wind action, it having been found 25 difficult to produce a die cut pivot support in hangers of the class described which will be self compensatory in its movement, so as to insure snug fits between the working parts to avoid rattling. In the present invention 30 the movable part of the hanger is constructed with a compensatory curve adapted to co-act with the stationary part of the hanger in a manner during the movement thereof so as to constantly snugly span a 35 distance between two points whereby rattling is prevented. In the drawings:

Figure 1 is a perspective view of the invention applied to a fragment of the frame and sash, but shown in the process of being 40 hung.

Fig. 2 is a side elevation of a part of the window frame and sash showing the hanger in its normal locked position.

Fig. 3 is a front view of the movable 45 hanger member.

Fig. 4 is a side view of a part of the window frame and sash showing the invention positioned as it appears when the window is held in its extreme outswung position, the 50 storm sash fastener means not being shown.

Fig. 5 is a front view of the stationary 55 member of the hanger.

Fig. 6 is a top view of the assembled hanger, the window frame not being shown, 55 and

Fig. 7 is an enlarged diagrammatic view illustrating the various stages of the movement of the movable member on the stationary member, showing the development of an irregular compensatory curve.

60

A represents a portion of the window frame, and B the window sash fitting into the opening of the frame. C designates the stationary supporting bracket member and D the supported movable sash supporting 65 member. The stationary member is struck from a flat sheet of metal and bent to form oppositely disposed alined screw plate parts to form the screw plate 1 having screw holes 2 whereby the member may be firmly screwed 70 to the lintel of the frame A either flush with or adjacent the edge thereof.

Centrally widthwise of the screw plate the latter is bent to form the outwardly extending 75 hook shaped hollow lug 2, having parallel spaced walls 3 forming collectively a relatively thick flat vertically disposed lug, the bend thereof being such as to produce a rounded outer surface constituting an outwardly and upwardly inclined edge 4. 80 Above, the lug is formed with a transverse upwardly opening V-shaped notch or crotch 5, one wall 6 thereof being shown parallel with the edge 4. Extending at right angles 85 to the wall 6, is, what may be termed the bottom of the crotch 7, the width thereof being such as to snugly receive the thickness of the metal sheet out of which the member D is struck. Continuing from the bottom 7 and extending upwardly and rearwardly 90 to the plate 1, and terminating a distance below the upper edge of the latter to form the blank space 8, is the wall 9 of the crotch. By making the lug as described, namely, 95 with a crotch having a wide opening and a relatively wide bottom, the male member of the die (not shown) employed in cutting the blanks (not shown) will be of durable shape having no acutely angled cutting parts, thereby simplifying and cheapening the 100 process of manufacture. The movable member D is formed with a fastening plate 10 having suitable screw holes 11 whereby it is firmly secured, as by means of screws, to the sash B. The underside of the fastening plate is flush, when mounted, with that 105 of the plate 1.

Extending upwardly and outwardly and beyond the top of the sash to a position directly opposite the member C (when the 110

- sash is in closed position) is the loop portion of the movable member. It is formed with a rectangular elongated opening 12 adapted to loosely receive the lug 2 widthwise, the angle of the loop portion being similar to the angle of the edge 4 so as to be parallel with the latter. The supported member is blanked so as to form when bent, two inturned oppositely and longitudinally disposed parallel cam lugs 13 extending a distance beyond the ends of the opening 12, so as to form a guide (Fig. 1) for directing the sash in the process of hanging. When the window is in closed position (Fig. 2) the upper edge 14 of the opening (which is in the state in which it left the die) seats squarely on the bottom 7 of the crotch the latter constituting a pivot bearing as is best shown in Fig. 7 of the drawings. Virtually, the supported member hangs in the vertex of said crotch.
- The cam lugs are formed with what may be termed a compensatory curve 14', or, in other words a curve so formed as to compensate for the change of position of the center of rotation 15 when the squared edge 14 is caused to turn on the bottom of the crotch 5. Three stages of this turning movement are illustrated by three kinds of lines (solid-heavy dash-and dot and light dash and dot) each indicating the relative position of the center 15 with respect to the face 16 of the plate 1. The position indicated in solid lines *a* requires the edge 35 of the cam lug to extend to *b* so as to permit no play between the face 16 and the wall 6. The heavy dash lines *c* indicate that the center 15 has moved toward the face 16, and that the distance between the latter and the center 15 has been shortened while the dotted lines indicate that the center 15 is again changed in position. Thus, the cam edge of the lugs is designed to compensate for the change in position of the center 15. By constructing the cam lugs as described no appreciable amount of play at any time exists between the wall 6 and the face 16, thereby preventing rattling of the sash in its hanger.
- To prevent rattling of the sash longitudinally, the curve of the edge 17 of the lug 2 is also developed from the movement of the center 15. In Fig. 4, the sash is shown extended as far as the usual sash fastener 55 mechanism at the bottom of the sash (not

shown) permits. The lower edge 18 of the opening 12 snugly passes over this edge when the sash is swung the curve changing in direction as the center 15 changes place. The member D is slightly offset at *e* to afford sufficient space for the cam lugs to operate in.

I claim:

1. In a hanger, a stationary supporting member including a plate, and an outstanding vertically disposed lug thereon formed at its top with an upwardly opening crotch and having a curved lower edge, and a supported window sash member having an opening of such shape as to movably receive said lug and be pivotally supported by means of the upper edge of said opening on the bottom of said crotch, the lower edge of said opening moving snugly over said curved lower edge when said supported member is moved, said supported member having a curved part extending from said pivotal support to said plate the curved face thereof being formed so as to snugly fit thereagainst during the movement of said supported member.

2. In a hanger, a stationary supporting member including a plate and an outstanding lug thereon formed at its top with an upwardly opening crotch, a supported sash member depending from said crotch so as to pivot on the bottom thereof, and lugs having a curved edge on the supported member extending rearwardly away from said pivot to said plate so that their curved edges will contact therewith whereby to maintain a snugly fitting relation between said supporting and supported member during the movement of the latter.

3. In a hanger, a stationary supporting member comprising in part an outstanding lug formed at its top with an upwardly opening crotch, a supported sash member having an aperture to loosely receive said lug and being adapted to be hung from above into said crotch so as to swing outwardly therefrom, said sash member being formed with spaced guide members extending over the sides of said lug to loosely receive said lug between them in the process of hanging the sash for the purpose set forth.

In testimony whereof I affix my signature.

ANTON SCHROEDER.
